UNITED STATES PATENT OFFICE.

KLAUS SOLLIE, OF YOUNGSTOWN, OHIO.

MINE-CAR.

1,338,046.

Specification of Letters Patent. Patented Apr. 27, 1920.

Application filed December 16, 1919. Serial No. 345,329.

To all whom it may concern:

Be it known that I, KLAUS SOLLIE, a citizen of the United States, residing at Youngstown, in the county of Mahoning and State of Ohio, have invented a new and useful Improvement in Mine-Cars, of which the following is a full, clear, and exact description.

The present invention relates broadly to 10 cars, and more particularly to that type known as mine cars.

The principal object of the present invention is to provide a car having an increased carrying capacity without any increase in the size of the car.

A further object of the invention is to provide a car of less height than that of cars ordinarily employed, but having an increased carrying capacity.

20 A still further object of the present invention is to provide a car having the main bottom portion thereof formed of wood, the remainder of the bottom and sides being formed of metal having wheel-receiving 25 openings therein.

Still another object of the invention is to provide a car having transversely extending bracing members with enlarged ends constituting coverings for the wheel receiving 30 openings formed in the metallic portion of the car body.

The foregoing and other objects, together with their attendant advantages, will be apparent as the invention becomes better understood by reference to the accompanying specification and drawings forming a part thereof, it being premised that changes may be made in the various details and the manner of operation within the scope of the 35 appended claims without departing from the spirit of the invention.

Figure 1 is a top plan view of a car constructed in accordance with the present invention.

45 Fig. 2 is a longitudinal sectional view of the car shown in Fig. 1, and

Fig. 3 is a transverse sectional view on the line III—III of Fig. 1.

It is obvious that mine cars are limited 50 so far as their outer dimensions are concerned, by the size of the entries through which the cars must pass. If the height of the cars is increased it will necessitate added labor on the part of the miners during the

loading of the cars, and will leave less room 55 between the upper edges of the car body and the roof of the mine entries. It is desirable that the sides of the cars be constructed as low as possible, but that the cars have a 60 large carrying capacity. It is the object of 65 the present invention to provide for the construction of such a car.

Experiments have shown that mine cars constructed entirely of metal are not capable of withstanding continued usage as the 70 bottoms thereof buckle and break. According to the present invention the cars are constructed with the main bottom portion thereof formed of wood and the remaining bottom portions and sides are formed of 75 metal.

Referring more particularly to the drawings, there is illustrated a mine car having the usual wheeled trucks 2 carrying a 80 wooden bottom 3. This bottom is preferably constructed of longitudinally extending planks of the desired thickness placed on opposite sides of a central metallic channel-shaped member 4 receiving the drawheads 5 at its opposite ends.

The main wooden bottom portion 3 supports auxiliary metallic bottom portions 6 which, in turn, support the metallic side and end portions 7 which may be secured thereto in any desired manner. The auxiliary metallic bottom portions 6 extending 85 on opposite sides of the main wooden bottom of the car are provided with wheel-receiving openings 8 into which the wheels are adapted to project. Cars as ordinarily constructed heretofore have had the metallic sides inclined upwardly away from the main bottom portion to provide sufficient room for the wheels. It is obvious that 90 with a construction of this type the carrying capacity of the car is materially decreased. According to the present invention, there are preferably provided hollow metallic transversely extending bracing members 9 having enlarged end portions 10 forming pockets coöperating with the wheel 95 openings 8 and forming coverings therefor. Due to the fact that each of these pockets 10 is only of sufficient size to form a proper housing for the wheels, the main interior portion of the car is unobstructed so that the carrying capacity thereof is materially increased.

2

Due to the provision of the transversely extending bracing members, the wooden portion of the bottom and the metallic portions are materially strengthened, thereby preventing sagging of the bottom. I also preferably provide triangularly shaped bracing plates 11 having flanges 12 permitting the same to be readily secured to the metal car sides and to the upper portions of each of the pockets 10. In this manner the sides of the cars are prevented from bulging.

The car is also preferably provided with channel-shaped or angle members 14 between the car bottom and the bearing boxes serving as additional ties for the floor and also tending to keep the boxes in place.

The advantages of my invention arise from a car construction in which the majority of the interior space of the car is rendered available for receiving the material being handled.

A further advantage results from the provision of the transversely extending bracing members performing the double function of bracing the car bottom and covering the wheel openings.

I claim:

1. A car having metallic sides and metallic bottom portions, said metallic bottom portions being provided with wheel receiving openings, a wooden bottom coöoperating with said metallic bottom portions, and bracing members extending transversely of the bottom portion and overlying said openings, substantially as described.

2. A car having metallic sides and metallic bottom portions, said metallic bottom portions being provided with wheel receiving openings, a wooden bottom coöoperating with said metallic bottom portions, and bracing members extending transversely of the bottom portion and having enlarged end portions overlying the wheel openings and

forming coverings therefor, substantially as described.

3. A car body provided with wheel receiving openings in the bottom thereof, and bracing members extending transversely of the bottom and forming coverings for said openings, substantially as described.

4. A car body provided with wheel-receiving openings in the bottom thereof, and hollow metallic bracing members extending transversely of the bottom, and forming covers for said openings, substantially as described.

5. A car body provided with wheel-receiving openings in the bottom thereof, and hollow metallic bracing members extending transversely of the bottom, said bracing members having enlarged end portions forming housings for the wheel openings, substantially as described.

6. A car body provided with wheel-receiving openings in the bottom thereof, bracing members extending transversely of the bottom and forming coverings for said openings, and bracing plates coöperating with said members, substantially as described.

7. A metallic car body provided with wheel-receiving openings in the bottom thereof, a main wooden bottom portion intermediate said openings, and bracing members extending transversely of the bottom and forming coverings for said openings, substantially as described.

8. A car body having wheel-receiving openings in the bottom thereof, and housing members coöperating with said openings, the housing members on opposite sides of the car body being connected by transversely extending bracing members, substantially as described.

In testimony whereof I have hereunto set my hand.

KLAUS SOLLIE.
